(57) **CLAIM**

The ornamental design for a body massaging device, as shown and described.

DESCRIPTION

FIG. 1 is a perspective view of my new design showing a body massaging device;

FIG. 2 is a top plan view thereof, a bottom plan view being a mirror image;

FIG. 3 is a front elevation view thereof;

FIG. 4 is a rear elevation view thereof; and,

FIG. 5 is a side elevation view thereof, the other side being a mirror image.

1 Claim, 2 Drawing Sheets

FIG. 1

FIG. 2

FIG. 3

FIG. 4
